JOHN CARROLL, OF PATERSON, NEW JERSEY, ASSIGNOR OF ONE-HALF TO ERNEST BARBER, OF PATERSON, NEW JERSEY.

BEAM-HEAD BRAKE FOR LOOMS.

Application filed August 5, 1924. Serial No. 730,211.

This invention has relation to the art of weaving and has particular reference to an improvement in a beam head brake for looms which brake constitutes the means for tensioning the warp threads.

At the present time, certain of the looms now in general use are provided with beam heads around which a rope is trained, the upper end of which rope is secured in any suitable manner and to the lower end of which a weight is attached, whereby the convolutions embracing the beam head serve to effect a braking action thereon to tension the warp threads. It has been found that in actual practice, the rope convolutions which embrace the beam head tend to stick at intervals so that a uniform tension is not obtained, thereby resulting in the production of cloth of uneven mesh and inferior quality. When this occurs, it becomes necessary to remove the rope from the beam head and rub the same with graphite, French chalk or other suitable substances which entail considerable time, causing a shutdown of the loom and a consequent loss to both the employer and employee. Furthermore the ropes rapidly wear to such an extent as to render them unfit for use thus requiring replacements frequently, all of which combine to add to the cost of production of the cloth.

It is therefore an object of the present invention to overcome the above recited objections and disadvantages, by interposing a contractile element or split sleeve between the beam head and the rope convolutions which embrace the same, so that relative movement therebetween and consequent wear on the rope is reduced to an absolute minimum; so that a uniform tension is exerted at all times on the warp threads and furthermore so that the introduction of a suitable substance between said element or sleeve and the beam head is facilitated; and this without materially altering the loom structure.

The invention furthermore contemplates an improved warp thread tensioning means for looms, which is comparatively simple in its construction, inexpensive to produce and install and which is highly efficient and thoroughly reliable in its purpose.

With the above recited and other objects in view, the invention resides in the novel construction set forth in the following specification, particularly pointed out in the ap-

pended claims and illustrated in the accompanying drawings, it being understood that the right is reserved to embodiments other than those actually illustrated herein, to the full extent indicated by the general meaning of the terms in which the claims are expressed.

In the drawings—

Figure 1 is an end view of the beam head equipped with a braking means constructed in accordance with the invention;

Fig. 2 is a sectional view therethrough taken approximately on the line 2—2 of Fig. 1;

Fig. 3 is a sectional view taken approximately on the line 3—3 of Fig. 2; and

Fig. 4 is a perspective view of the split sleeve or contractile element.

Referring to the drawings by characters of reference 10 designates a warp beam which has secured to its opposite ends the usual beam heads 11 which consist of a cylindrical body 12 having a closed inner end 13 which is attached in any suitable manner thereto. The outer periphery of the beam head is provided at its opposite side edges with circumferential flanges 14 to define the usual drum or spool around which the convolutions 15 of the usual rope 16 are trained, the rope 16 being attached at its upper end as at 17 to any suitable element and having supported at its lower end a weight 18 whereby the weight effects a normal contraction of the convolutions. The improvement which constitutes the present invention consists in interposing between the convolutions 15 of the rope and the periphery of the drum or cylindrical body 12 a split sleeve 19 which conforms in shape to the periphery of the body or drum 12 and which snugly fits thereabout with its opposite ends spaced apart. Under this arrangement it will thus be seen that the split sleeve 19 which is surrounded by the convolutions 15 of the rope has no relative movement with respect thereto and that the periphery of the beam head moves or turns relative to the sleeve 19. This prevents wear on the rope convolutions and increases the length of life or usefulness of the rope to an absolute maximum.

It is furthermore found that the sleeve which is preferably of a suitable anti-friction metal exerts a uniform contractile braking action at all times on the beam head which tends

2
toward the production of a uniform tension on the warp threads.

In order to facilitate the introduction of a suitable lubricant substance, such as graphite or the like to the confronting inner and outer peripheries of the sleeve and beam head, the said cylindrical wall 12 of the beam head is apertured as at 20. Furthermore in order to provide means for supplying the lubricant substance automatically to said peripheries the said aperture 20 is preferably threaded to receive the threaded nozzle 21 of a lubricant cup 22 which is closed at its outer end by a screw cap 23 which may also serve as a means for forcing the lubricant through the nozzle upon rotation of the cap in one direction.

It is of course to be understood that where a reliable anti-friction metal is employed such as "Monel", the necessity of employing the lubricating device is obviated.

From the foregoing it will thus be seen that an extremely simple and inexpensive improvement in beam head brakes has been devised which serves to effect the production of cloth of a uniform texture.

I claim:

1. The combination with the beam head of a loom and a brake rope coiled thereabout, of a split contractile sleeve interposed between the convolutions of said brake rope and beam head and a perforated portion of said beam head constituting means for introducing a lubricating substance between the outer periphery of the beam head and the inner periphery of the sleeve.

2. The combination with the beam head of a loom and a brake rope coiled thereabout, of a split contractile sleeve interposed between the convolutions of said brake rope and beam head and a perforated portion of said beam head constituting means for introducing a lubricating substance between the outer periphery of the beam head and inner periphery of the sleeve and means communicating with said perforated portions for holding a supply of lubricant.

3. The combination with the beam head of a loom and a brake rope coiled there-

about, of a split contractile sleeve interposed between the convolutions of said brake rope and beam head and a perforated portion of said beam head constituting means for introducing a lubricating substance between the outer periphery of the beam head and inner periphery of the sleeve and means communicating with said perforated portions for holding a supply of lubricant, said means being rotatable with the beam head for periodically effecting the gravitational feeding of the lubricant therefrom.

4. A let-off mechanism for looms including, with the warp-beam having a hard encompassing cylindrical surface, means to resist rotation of the beam including a tautened flexible element constricting the part of the beam having such surface, and a band of sheet material interposed between the beam and the constricting portion of said element and having an inner hard smooth cylindrical surface conforming and in contact with said surface of the beam.

5. A let-off mechanism for looms, including, with the warp-beam having a hard encompassing braking surface, means to resist rotation of the beam including a tautened flexible element constricting the part of the beam having such surface, and a band of sheet material interposed between the beam and the constricting portion of said element and having an outer hard smooth cylindrical surface receiving the contact of said portion.

6. A let-off mechanism for looms including, with the warp-beam having a hard encompassing cylindrical surface, means to resist rotation of the beam including a tautened flexible element constricting the part of the beam having such surface, and a band of sheet material interposed between the beam and the constricting portion of said element and having an inner hard cylindrical surface conforming and in contact with said surface of the beam and an outer hard smooth cylindrical surface receiving the contact of said portion.

JOHN CARROLL.
